UNITED STATES PATENT OFFICE

2,665,933

DOOR LATCHING MECHANISM

Roy W. Hardwick, Freehold, N. J., assignor of
fifty per cent to Frank W. Hardwick, Newark,
N. J.

Application October 2, 1950, Serial No. 187,996

2 Claims. (Cl. 292—181)

1

The present invention relates to new and useful improvements in automatic nest openers and more particularly to the provision of time-controlled, electrically operated releasing means for the nest door to permit the latter to swing into an open position.

An important object of the invention is to provide means for locking a plurality of nest doors in closed position and with electrically controlled releasing means to simultaneously open the doors.

A further object of the invention is to provide an electromagnetically operated catch for releasing the door locking mechanism and in which the mechanism is automatically set by the closing of the doors.

A still further object is to provide a device of this character of simple and practical construction, which is efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of a row of nests, showing one of the doors closed for resetting the door releasing mechanism;

Figures 2 and 3 are enlarged vertical sectional views taken respectively on the lines 2—2 and 3—3 of Figure 1;

Figure 4 is an enlarged vertical sectional view of the door locking and releasing mechanism;

Figure 5 is a fragmentary vertical sectional view of the door locking and releasing tube and the catch for one of the doors to reset the releasing mechanism;

Figure 6 is an enlarged fragmentary sectional view taken on the line 6—6 of Figure 1; and

Figure 7 is an enlarged fragmentary perspective view of one of the springs for opening the doors.

Referring now to the drawings in detail, wherein, for the purpose of illustration, I have disclosed a preferred embodiment of the invention, the numeral 5 designates tiers or rows of nest compartments 6, each tier or row being provided with a single door 7 for closing the several openings to the compartments. The doors 7 are hinged to the front of the nests by conventional hinge structures 8 for swinging upwardly into a closed position and a wire spring 9 is attached to each door for swinging the same downwardly quickly into an open position.

2

The door locking and releasing mechanism comprises a barrel or tubular casing 10 recessed in a vertical position to the front of the rows of nests adjacent the center thereof and secured thereto by straps 11. A door locking or releasing tube 12 is slidably mounted in the barrel or casing 10, the inner tube 12 and the outer casing 10 being formed with registered openings 13 and 14, respectively, at the front thereof.

10 The upper end of the barrel or casing 10 is provided with a threaded cap 15 and a coil spring 16 is held under tension between the cap and the upper end of the inner tube 12.

The uppermost door, indicated at 17, is provided with a rigid catch 18 having an inclined upper edge 19 which raises the inner tube 12 as the catch enters the opening 13 thereof by a raising movement of the door 17, in a manner as will be apparent from an inspection of Figure 5 of the drawings. The remaining doors 7 are provided with pivoted spring actuated catches 20 to enter an adjacent opening 13 of the inner tube 12 after the latter has been moved into its raised position by the catch 18, the doors thus being held in a locked position by reason of the engagement of the catches with the inner tube.

An electromagnet 21 is enclosed in a housing 22 at the lower end of barrel or casing 10 and controls a pivoted catch 23 engaged in a slot 24 in the lower end of inner tube 12 to hold the inner tube in its raised position. The catch 23 is moved into engagement in the slot 24 by spring means (not shown) and is released from the slot when the electromagnet 21 is energized to release the inner tube 12 which is then moved downwardly by spring 16. A stop 25 underlies the lower end of the inner tube 12 to limit its downward movement and to hold the openings 13 in position for entering the catches 18 and 20 therein.

40 A push-button type switch 26 is connected in the circuit with the electromagnet 21 and is positioned in the path of closing movement of one of the doors 7 to close the switch for the magnet. The magnet is also connected with a conventional type of electric time control mechanism (not shown) to energize the magnet at a predetermined time of day.

Having described the invention, what is claimed as new is:

50 1. A door locking mechanism comprising an elongated tube having closed upper and lower ends, a locking plunger slidably disposed within said tube, a spring seated in the upper end of said tube and urging the plunger downwardly, a spring urged catch in the lower end of said tube engaging the lower end of said plunger and

preventing downward movement of the plunger, said tube and plunger having aligned apertures therein, said plunger aperture being smaller than said tube aperture, a door latch moveable into said apertures having a cam shaped upper surface and a depending end lug, seating against the inner surface of said plunger, means for automatically releasing said catch, said plunger engaging said latch cam surface upon release of the catch and forcing the same outwardly from the aligned apertures.

2. A door locking mechanism comprising an elongated tube having closed upper and lower ends, a locking plunger slidably disposed within said tube, a spring seated in the upper end of said tube and urging the plunger downwardly, a spring urged catch in the lower end of said tube engaging the lower end of said plunger and preventing downward movement of the plunger, said tube and plunger having aligned apertures therein, said plunger aperture being smaller than said tube aperture, a door latch moveable into said apertures having a cam shaped upper surface and a depending end lug, seating against the inner surface of said plunger, means for

5 automatically releasing said catch, said plunger engaging said latch cam surface upon release of the catch and forcing the same outwardly from the aligned apertures, said catch comprising a pivoted lever, movement of said latch into said apertures moving said plunger upwardly against the action of said spring and causing said catch to engage the lower end of said plunger.

ROY W. HARDWICK.
